(57) CLAIM

The ornamental design for a sports rosary, substantially as shown and described.

DESCRIPTION

FIG. 1 is a front view of a sports rosary showing my new design;

FIG. 2 is a front view of a second embodiment of FIG. 1;
FIG. 3 is a rear view of the embodiment shown in FIG. 2.
FIG. 4 is a front view of a third embodiment FIG. 1;
FIG. 5 is a rear view of the embodiment shown in FIG. 4;
FIG. 6 is a front view of a fourth embodiment of FIG. 1;
FIG. 7 is a rear view of embodiment;
FIG. 8 is a front view of a fifth embodiment of FIG. 1;
FIG. 9 is a front view of a sixth embodiment of FIG. 1; and,
FIG. 10 is a front view of a seventh embodiment of FIG. 1.
The broken lines are for illustrative purposes only and form no part of the claimed design.
